I. W. Gibbs, of Albany, N. Y.

Assignor to

North, Chase & North, of Philadelphia, Pa.

Letters Patent, No. 899, Dated June 23, 1857.

The schedule referred to in these Letters Patent, and making part of the same.

To all whom it may concern:

Be it known that I, I. W. Gibbs, of the City and County of Albany, and State of New York, have invented or produced a new and original design for stoves, and I do hereby declare that the following is a full and exact description of the same, reference being had to the accompanying drawings, in which

Des. 899.

- " 2. " a front plate and doors.
- " 3. " an end of the oven with the door attached.
- " 4. " a top plate over the fire.
- " 5. " a plate in front of the oven.
- " 6. " a hearth plate.
- " 7. " a side plate.
- " 8. " a foot and damper.

What I claim as my invention and desire to secure by letters patent, is the design and configuration of the moldings and ornaments, as herein described, forming an ornamental design

A. S. M. for stoves.
